UNITED STATES PATENT OFFICE.

BYRON VAN WIE, OF TROY, NEW YORK, ASSIGNOR OF FIVE-SIXTHS TO
WILLIAM F. GREENE, OF SAME PLACE, AND W. EVERETT JOHNSON,
OF NEW YORK, N. Y.

CENTRIFUGAL MACHINE.

SPECIFICATION forming part of Letters Patent No. 478,484, dated July 5, 1892.

Application filed August 22, 1891. Serial No. 403,425. (No model.)

To all whom it may concern:

Be it known that I, BYRON VAN WIE, of Troy, in the county of Rensselaer and State of New York, have invented certain new and 5 useful Improvements in Centrifugal Extractors; and I do hereby declare that the following is a full, clear, and exact description thereof, reference being had to the accompanying drawings, and to the letters of reference 10 marked thereon, which form part of this specification, in which—

Figure 1 is a side elevation, partly broken, of my improved drive for centrifugal extractors and similar revolving machinery. Fig. 2 15 is a central vertical sectional view of the same. Figs. 3, 4, and 5 are details.

This invention is an improvement in centrifugal extractors, or machines for separating liquids from solids or liquids of different 20 gravities for drying cloths, &c., by separating the water therefrom, and for many purposes in the arts where it is desired to speedily separate bodies of different specific gravity by revolving them rapidly in a suitable 25 holder, so that the lighter or less tenacious substance will be separated from the heavier and denser substance by centrifugal action and thrown out of the vessel.

The present invention is designed to permit 30 the extractor or separating-vessel to gyrate freely while revolving, so that the substances being treated can shift freely in the vessel without any damage to or strain upon the driving mechanism, which, however, will 35 always tend to cause the vessel to assume and keep a horizontal position while revolving.

The invention consists in the novel construction of the supporting devices for the revoluble extractor and in the novel construction 40 and connection of the devices for imparting rotary motion thereto, all of which will be clearly understood from the following description and concisely summarized in the claims.

Referring to the drawings by letters, A 45 designates the base of the machine, securely fastened to a suitable foundation, and B a short vertical shaft fixed in a socket in base A.

C is a metallic dish pinned on top of shaft 50 B, its upper face being concaved, as shown,

and having a slight flange c on its edge. These parts are stationary. D is a carrier-block, having an enlarged head D', convexed on its bottom to fit in the concave dish C, and from it rises a vertical tapered stub-shaft d, 55 which may be integral with the head, but is preferably a separate piece set in a socket therein, so as to be replaceable when worn, and washers d' may be put in the socket beneath the end of shaft d to vertically adjust 60 the latter.

The cylindrical-extractor vessel E is of ordinary form, except that its bottom has a central perforated stud e, which fits on stub-shaft d, and thus supports and centers the 65 extractor thereon. As shown, the sides of the extractor are perforated, and it has an inwardly-projecting flange e' at top to prevent the contents running over the sides thereof. The extractor may be inclosed by a station- 70 ary casing e², as usual.

E' E' are perforated ears depending from the bottom of the extractor at points diametrically opposite each other and pivotally connected by pins f f to the opposite sides of a 75 ring or annulus F of greater diameter than dish C.

Ring F is again pivotally connected by pins F' F' to upstanding ears g g on a similar lower ring G, pins F' F' being on a line at right angles to pins f f. From ring G depends ears G' G' at points intermediate ears g g, which are pivotally connected by pins h h to a ring H, lying below ring G, and this ring H is pivotally connected at points intermediate pins 85 h h to pins i i, projecting from opposite sides of the hub of a pulley I, loosely journaled on shaft B between base A and dish C. The rim of this pulley depends toward the base, so as to give ample room for belting it to a proper 90 drive. By this construction it will be seen that the extractor is driven by universal-joint or gimbal-ring connections from a pulley on a fixed shaft, so that the oscillation or tilting of the extractor does not affect the pulley nor cause it to bind on the shaft, as the oscillation will be compensated for between the ring F and extractor or between rings F and G.

If the extractor oscillates or tilts to one side, block D shifts its position easily in 95 100

dish C and the whirl of the extractor is uninterrupted thereby, and the opposed concavo-convex faces of the dish and block cause the block to shift back to the center of dish and 5 bring the stub-shaft to a vertical position, and hence if the contents of the extractor shift during its revolution by any cause the support and drive instantly begin to bring it back to proper horizontal smooth-running position.

The extractor can be tilted to one side to facilitate filling thereof without injury to its drive, or by simply removing pins *ff* it can be lifted off the support and another extractor 15 can be placed thereon, if desired.

It will be observed that the entire weight of the extractor and its contents is transferred direct to the fixed base and no weight is carried by the pulley or drive.

20 The flange *c* limits the lateral movement or oscillation of the extractor and also serves to confine the lubricant in dish C.

The number of gimbal-rings or construction of universal connection might be slightly varied without departing from my invention, which consists in making the connection between the drive and extractor so that oscillation or gyration of the latter will not affect the former, and in so constructing the supports of the extractor they will tend to restore 25 it to an equilibrium when it is revolved.

Having thus described my invention, what I claim as new, and desire to secure by Letters Patent, is—

30 1. In a centrifugal extractor, the combination of the extractor and a support therefor with gimbal-rings connected to the extractor and means for revolving the rings, and thereby driving the extractor, substantially as described.

35 2. In a centrifugal extractor, the combination of the extractor, a support therefor, a drive mechanism, and universal-joint connections between the same for revolving the latter and extractor independently of the support, substantially as described.

40 3. The combination of the concave-surfaced support with the convex-faced block resting thereon and the stub-shaft fixed to said block and engaging a socket in the bottom of the extractor, substantially as specified.

45 4. The combination of the concave support, the convex-faced block resting thereon, and a stub-shaft on said block with the extractor

55 mounted on said stub-shaft and mechanism for revolving said extractor, substantially as described.

5. The combination of the concave support, the convex-faced block resting thereon, and a stub-shaft fixed to said block, and the extractor mounted on said stub-shaft with the gimbals connected to said extractor and means for driving the same, substantially as specified.

6. The combination of the revoluble extractor loosely mounted on a fixed shaft, but 60 independent thereof, and the pulley loosely journaled on shaft below the extractor with the universal connections between said pulley and extractor for driving the latter and retaining it on the shaft, substantially as described.

7. The combination of the revoluble extractor loosely supported on the top of a fixed shaft, the pulley loosely journaled on said shaft below the extractor, and the gimbals 75 pivotally connecting said pulley with the extractor, constructed and arranged substantially as and for the purpose described.

8. The combination of the dish fixed to the upper end of a vertical shaft, the convex-faced block sitting in said dish, the extractor mounted on said block, and the gimbals connected to the extractor and to a drive-pulley 80 loosely journaled on said shaft, all substantially as and for the purpose described.

85 9. The combination of the concave dish, the convex-faced block resting therein, the stub-shaft fitting in a socket in said block, and the extractor mounted on said block and centered by said stub-shaft, and means for revolving 90 said extractor, substantially as specified.

10. The combination of the concave dish mounted on a fixed support, the convex-faced block resting therein, the stub-shaft fitting in a socket in said block, and the extractor fitted on said stub-shaft with the series of gimbal-rings below the extractor, the uppermost being pivotally connected to the extractor and the lowermost to the revolving hub, all 95 constructed and arranged substantially as and for the purpose set forth.

In testimony that I claim the foregoing as my own I affix my signature in presence of two witnesses.

BYRON VAN WIE.
